(57) **CLAIM**

The ornamental design for a docking station for tablet computer as shown and described.

DESCRIPTION

FIG. 1 is a perspective view of a docking station for tablet computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the portion labeled "8" in FIG. 6;

FIG. 9 is an enlarged view of the portion labeled "9" in FIG. 6;

FIG. 10 is a cross-sectional view taken along line 10-10 in FIG. 8;

FIG. 11 is a cross-sectional view taken along line 11-11 in FIG. 9; and

FIG. 12 is a perspective view thereof with the tablet computer being inserted.

The dashed broken lines illustrate portions of the docking station for tablet computer that form no part of the claimed design. The dot-dash broken lines represent the boundaries of the claimed design, and form no part thereof. The dashed broken lines showing a tablet computer in FIG. 12 are for the purpose of illustrating environmental structure, and form no part of the claimed design.
